INVENTOR:

Robert F. Dobson.

United States Patent Office.

ROBERT F. DOBSON, OF GODERICH, CANADA.

Letters Patent No. 80,613, dated August 4, 1868.

IMPROVED BROOM.

The Schedule referred to in these Letters Patent and making part of the same.

TO ALL WHOM IT MAY CONCERN:

Be it known that I, ROBERT F. DOBSON, temporarily of Goderich, in the county of Huron, and Dominion of Canada, have invented a new and useful Improvement in the Manufacture of Brooms; and I do hereby declare that the following is a full, clear, and exact description of the same, sufficient to enable one skilled in the art to which my invention appertains to fully understand and use the same, reference being had to the accompanying drawings, forming a part of this specification, and in which—

Figure 1 is a top view of the "turning-ring."

Figure 2 is a side view, showing the corn as first secured to the handle, which is inserted into the holding-barrel, preparatory to the operation of turning the corn.

Figure 3 is a side view, representing the corn as having been drawn partly through the turning-ring, and in a position to be bound.

Figure 4 is a side or front view of the broom as completed.

My invention relates to an improvement in the mode of securing the broom proper, or the corn, to its handle, and it consists, first, in so fastening the broom-corn that the free portions shall extend towards the upper end of the handle, and then bending or turning the said corn back upon itself, and there securing it, as will herein-after be more fully described.

Similar letters of reference indicate corresponding parts in the several figures.

In carrying out my invention, I take the corn, E E, and first well secure it, at F, around the handle C, near the lower end of the latter. By reference to fig. 2 of the drawing, it will be seen that, at this stage in the manufacture, the free portion of the corn, which it is intended shall ultimately constitute the sweeping-surface, is extended toward the upper end of the handle.

D represents a barrel of the kind employed on rolling-machines in common use. From one end of this barrel extend braces B B, which support, at their outer extremities, the ring a. The corn having been secured to the handle, as above described, the said handle is inserted downward through the ring a and barrel D, as shown in fig. 2. The ring a, passing up under the corn, causes the same to spread, as represented.

The handle is now drawn downward through the barrel and ring, carrying with it the corn, which is doubled back upon itself, or turned inside out, and caused to assume the position shown in fig. 3 of the accompanying drawings. The broom is pressed into shape for sweeping, in any of the known forms, and there secured, either in the usual manner, that is, sewing with twine, or it is surrounded with a narrow band of metal, represented at g in fig. 4. If this latter course is pursued, the band is secured to the upper part of the handle by a rivet, H.

From the above description of my invention, it will be seen that a much-improved article is produced as readily, in every respect, as the ordinary broom, durability, neatness, and simplicity being advantageously combined in its structure.

The corn, being doubled back, is bent partly around the fastening-wire, and is thus prevented from working out from under the same while the broom is in use. When the fastening-band is used, much time is saved in the manufacture, and the handle is prevented from being pulled out of the broom.

I do not wish to claim broadly the use of the metallic fastening-band, as I am aware that something of the kind has been used before.

Having thus described my invention, what I claim as new, and desire to secure by Letters Patent, is—

1. The turning-ring a, affixed to the rolling-barrel D by means of the braces B, substantially as herein shown and described, for the purpose set forth.

2. As a new article of manufacture, a broom in which the corn is applied and secured as herein shown and described.

Certified to be the specifications referred to in the drawings hereunto annexed.

Dated, at Goderich, in the county of Huron, Dominion of Canada, this 17th day of February, 1868.

ROBERT F. DOBSON.
